UNITED STATES PATENT OFFICE.

WALTER E. HOLLAND, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

BATTERY-FILLING DEVICE.

Application filed June 4, 1921. Serial No. 474,895.

This invention relates to apparatus for supplying liquid to battery cells and more especially for filling storage battery cells to a predetermined level with water or electrolyte.

One object of the invention is to provide a device of the class noted which is particularly adapted to cause an alarm to be given when the liquid in a battery cell being filled has risen to a predetermined level, and 10 said device is particularly designed to be of durable and substantial construction, for which purpose it is made of such materials as will not appreciably deteriorate or dissolve in and contaminate the electrolyte under conditions of use.

A further object of the invention is to provide a battery filling device which shall include novel means for automatically cutting off the flow of liquid when it is removed from 20 the battery cell, the arrangement of parts being such that flow of liquid is permitted only when it is properly manipulated after its nozzle has been applied to or inserted in the filling opening of a battery cell.

I also desire to provide a battery filling device which shall include two relatively movable parts for controlling the flow of liquid, together with novel means whereby said parts are normally retained in such positions 30 as to prevent such flow.

Another object of my invention is to provide a filling device which shall require the exertion of force on the part of the user to maintain its relatively movable parts in such 35 positions as to allow flow of liquid and which shall include automatic means for cutting off the liquid flow when such force ceases or is not exerted.

These objects and other advantageous ends 40 I attain as hereinafter set forth, reference being had to the accompanying drawings, in which

Fig. 1 is a plan of a battery filling device constructed in accordance with my invention;

Fig. 2 is a longitudinal vertical section on the line 2—2, Fig. 1;

Figs. 3 and 4 are sections respectively taken on the lines 3—3 and 4—4, Fig. 2; and

Figs. 5 and 6 are transverse sections on the lines 5—5 and 6—6, Fig. 2.

In the above drawings, 1 represents a tubular handle of hard rubber or other suitable

insulating material which at its outer end is provided with a tubular extension 2 of reduced diameter having annular serrations designed to receive and hold a flexible rubber tube or pipe. The opposite end of said handle which is preferably also of reduced diameter, has fixed to it a valve head 3 maintained in position by radially extending set screws whose heads project beyond its outer surface. Said head 3 is hollow and its projecting portion is frusto-conical in form, having through its inclined side a port or passage 5 communicating through its interior cavity with the passage through the handle 1.

Rotatably mounted on this head is an angular nozzle structure made in two parts 6 and 7 threaded or otherwise fastened together and the latter of these parts terminates in a portion 8 of reduced diameter designed to fit into the filling opening or well of a storage battery cell. The part 6 of the nozzle is formed with a conical seat for the reception of the frusto-conical end of the head 3 and has a cavity 9 opening on said seat in position to register with the passage or port 5 of the head when said nozzle occupies a definite position thereon. This cavity also communicates with the axial passage through the tubular portion 8 of the nozzle so that there is provided a continuous passage from the handle 1 through the head 3 and the parts 6 and 7 of the nozzle, which however may be interrupted or cut off by turning the valve head 3 through an angle of approximately 90°. The passage 5 is thus closed off from the cavity 9 of the nozzle section 6, as shown in Fig. 4.

For normally retaining the valve head 3 and handle 1 in and returning them to a definite position in relation to the nozzle cavity 9, with the port 5 closed, I provide a series of rubber bands extending between the handle 1 and the rear projection of the nozzle section 6 preferably at an angle to the axial line thereof, for which purpose I provide on said handle a flange 10 having its edge formed with recesses 11 designed to constitute hooks 13 over which the rubber bands 12 may be placed. The nozzle section 6 is preferably extended rearwardly beyond the head 3 and its overhung edge is formed with perforations 14 for the reception of the second end of each of the rubber bands. Each of

these perforations is staggered or offset relatively to the hooks 13 when the port 5 is closed or cut off from the cavity 9 of the nozzle, so that when the rubber bands 12 are applied as indicated in Fig. 1, they tend to maintain said port closed, with the projecting heads of the screws 4 respectively against the ends of the slots 16 in the nozzle section 6. These slots, which extend circumferentially, are of such length as to permit of the valve head 3 being turned in the nozzle sufficiently far to bring the port 5 into communication with the cavity 9 of the nozzle, although obviously the rotation of the valve head necessary to bring the parts into these positions is opposed by the rubber bands, which when the turning force is removed, return said parts to their normal positions. It is to be noted that in addition to the above functions the rubber bands serve to hold together the nozzle and handle structures and at the same time insure the perfect engagement of the parts of the valve.

When it is desired to utilize the apparatus above described, the extension 2 of the tubular handle is connected through a suitable rubber or other flexible conduit with a source of liquid, such as an elevated reservoir, from which such liquid is free to flow through the handle 1 and into the head 3. Its passage through the port 5, however, is cut off by the valve section 6 which is normally so held by the rubber bands 12 as to close this port.

Under conditions of use the outer or free end 8 of the nozzle is introduced into the filling opening of a battery cell and the handle 1 is turned axially against the action of the rubber bands until the port 5 is brought into communication with the cavity 9 of the nozzle whereupon liquid flows through the handle and out of said nozzle into the cell. When the proper amount of liquid has been added to the cell, the handle and valve head are allowed to return to the normal closed position by the action of the rubber bands. If the nozzle is removed from the cell before allowing the valve to close, the flow of liquid is automatically cut off, since the rubber bands act to rotate said nozzle on the head 3, and thus close the port 5, as soon as it is no longer held from rotating by the walls of the cell opening.

In order that the operator may be advised when the liquid delivered from the nozzle has risen to a predetermined height in the battery cell or other container being filled, I provide on the reduced end 8 of the nozzle two terminals consisting in the present instance of strips or bars 17 of lead alloy or other electrical conductor not affected by the electrolyte of the cell or other liquid delivered through the nozzle. In the present instance these terminals consist of cast bodies of lead alloy in undercut grooves extending

longitudinally on opposite sides of the nozzle and they extend through the flange 18 into cylindrical cavities which they fill as indicated at 19.

Suitably insulated electrical conductors 20 extend through passages in opposite sides of the nozzle structure and terminate in said cavities where the lead of the terminals is preferably cast around the bared ends of them so that said exposed ends as well as the adjacent insulation are completely surrounded and enclosed. Said conductors 20 are preferably also led through channels in the enlarged portion of the handle 1 and are connected in circuit with a suitable signal device and current source.

While I have described the device as being made chiefly of hard rubber or a similar insulating material, I may preferably in certain cases, as for instance when for use in filling alkaline battery cells, make only the nozzle 7 of insulating material, to carry the contact terminals 17, and make the remaining body parts of a suitable metal, to save expense.

When under conditions of use the liquid in the battery cell is brought to such a height as to electrically connect the ends of the terminals 17, the circuit in which said terminals are included is thereby completed and the resulting current flow, by actuating a relay which closes the signal circuit, gives audible or other indication that sufficient liquid has been delivered to the cell. As above noted, the metal of the terminals 17-19 is not corroded by the electrolyte of the battery and the metal of the conductors 20 is likewise protected from injury since these are covered with electrolyte-proof insulation and their free ends are imbedded in the bodies 19 of the terminals. Furthermore, the body parts and valve-actuating springs 12 are non-corrodible since they are made respectively of hard and soft rubber or equivalent electrolyte-proof materials.

When used to add electrolyte rather than water, it is obvious that I may employ but a single conductor 19 and terminal 17 in connection with the alarm circuit for use with my device, since the electrolyte being delivered therethrough is itself an electrical conductor and may be connected with said circuit at any desired point.

The words "electrolyte-proof" used herein are intended to describe the insoluble character of certain materials when subjected to the action of the common storage battery electrolytes, which are, for instance, sulphuric acid solution in the lead-acid type of battery and a caustic alkali solution in the nickel-iron type of battery.

I claim:

1. The combination in a battery filling device of a tubular handle having a delivery nozzle made of electrolyte-proof insulating

material; electrolyte-proof metallic conductors carried by said nozzle and terminating in the same plane at the delivery end thereof; with insulated conductors imbedded in the 5 material of the nozzle and having their metallic portions surrounded by and enclosed within said terminal conductors.

2. The combination in a battery filling device of a tubular handle having a flange; a 10 nozzle of electrolyte-proof material mounted on said handle and having a passage cooperating therewith to constitute a valve; and rubber bands extending from said flange to said

nozzle structure in position to normally maintain said valve closed. 15

3. The combination in a battery filling device of a tubular handle having a head; a nozzle rotatably mounted on said head and overhanging the rear portion thereof; projecting portions on the handle, there being ports in the head and in the nozzle cooperating to 20 form a valve; with rubber bands extending between the projecting portions of the handle and the overhung portion of the head to normally maintain said valve closed.

WALTER E. HOLLAND.
